UNITED STATES PATENT OFFICE.

ERLE H. HAND, OF STAPLETON, NEW YORK.

PHONOGRAPHIC DISK-RECORD CABINET.

Application filed March 29, 1922. Serial No. 547,774.

To all whom it may concern:

Be it known that I, ERLE H. HAND, a citizen of the United States, residing at Stapleton, borough of Richmond, State of New York, have invented a new and useful Phonographic Disk-Record Cabinet, of which the following is a specification.

In phonographic disk record containers or ejectors, wherein a series of vertical, closely related, parallel compartments are employed, it has been found in practice that the partitions from which these compartments are formed are sometimes liable to buckle or warp owing to climatic or other conditions, and one object of my invention is to construct these partitions of such a character or contour, that warping will be prevented by the removal of certain portions of the material from which said partitions are made so as to form tongues, the latter being preferably held in assembled position by spacing strips or their equivalents through which pass horizontally disposed tie rods, or similar fastening devices.

My invention further consists of record holding compartments formed by partitions of the general character above referred to, and provided with pivoted levers which form the bottoms of the compartments and which have their rear portions widened so as to properly contact with the lower portion of the record to be ejected, so as to enable the desired record to be positively and accurately ejected under all conditions.

It further consists in a novel construction of an ejector bottom, which may be recessed so as to provide a seat into which a record may drop when in its rearmost stowed or housed position, in conjunction with an ejector lever which upon being actuated will effect or permit the ejection of a desired record by the action of gravity.

It further consists of other novel features of construction, all as will be hereinafter fully set forth.

For the purpose of illustrating my invention, I have shown in the accompanying drawings forms thereof which are at present preferred by me, since it will give in practice satisfactory and reliable results, although it is to be understood that the various instrumentalities of which my invention consists can be variously arranged and organized and that my invention is not limited to

the precise arrangement and organization of these instrumentalities as herein shown and described.

Figure 1 represents a perspective view of a record holding compartment, showing the upper rear edge of the partition from which the record is formed as being removed and a cut-out portion also in the bottom edge of said partition.

Figure 2 represents a section on line 2-2 of Figure 1.

Figure 3 represents on an enlarged scale a plan view of the ejector lever seen in Figures 1 and 2.

Figure 4 represents a perspective view of another form of record holding compartment showing another form of partition and levers which may be employed.

Figure 5 represents a section on the line 5-5 of Figure 4.

Figure 6 represents on an enlarged scale, 75 a plan view of the ejector lever seen in Figures 4 and 5.

Figure 7 represents a side elevation of a record holding compartment, wherein the upper edges of the partition converge, and wherein a forwardly and downwardly inclined recessed or slotted bottom is employed into which the records drop when in their rearmost or stowed position, said bottom being shown in section.

Figures 8, 9, 10 and 11 represent side elevations of other embodiments of my invention, showing various forms of partitioning devices and ejector levers which may be employed, the bottoms of the compartments being shown in section.

Figure 12 represents a plan view of a portion of a blank which is adapted to serve as the bottom of a record holding compartment.

Figure 13 represents on an enlarged scale, the manner of cutting or slitting the blank seen in Figure 12.

Figure 14 represents a plan view of Figure 15, showing the manner of securing the vertical parallel partitions between the tongues of the metallic base employed.

Figure 15 represents on an enlarged scale a plan view of a portion of Figure 14.

Figure 16 represents a front elevation of 105 a completed ejector, provided with the metallic base formed with the upwardly projecting tongues and partitions held between

said tongues, said tongues being omitted for clearness of illustration.

Figure 17 represents a perspective view of Figure 16. Figures 18 to 22 represent 5 modifications, showing a metallic front employed.

Similar numerals of reference indicate corresponding parts.

Referring first to Figures 1, 2 and 3, 1 10 designates an ejector skeleton, which is composed of partitions 2, having the vertical front edge 3, the top tongue 4, the rearwardly inclined edge 5, which merges into the horizontal edge 6, which terminates in 15 the vertical tongue or edge 7. The bottom edge of the partition 2 has a recess 8 therein, which is formed by the cut-out portion composed of the horizontal wall 9 and the vertical walls 10 and 11, whereby the two bottom 20 tongues 12 and 13 are formed. The upper edges or tongues of the partitions 2 are spaced apart by means of the horizontal spacing strips 14, while the bottom tongues 12 and 13 are spaced apart and gripped between 25 the spacing strips 15, and the rear tongues 7 are gripped between the vertical spacing strips 16, the strips 15 and 16 being of uniform or standard size or length.

The ejector levers 17 are composed of the 30 comparatively narrow front portion 18 and the widened rear portion 19, and are fulcrumed by the rod 20 passing through the hole 21, which is located in advance of the center of gravity of the lever, as seen in 35 Figure 3. The spacing strips 14 are held in assembled position by one or more tie rods 22, while the rear tongues 7 are held in assembled position by one or more tie rods, 23, while the bottom tongues 12 and 13 are 40 held in assembled position by the tie rods 24 and 25, it being of course understood that one or more of said tie rods may be employed, according to requirements.

The disk record is indicated at 26 and the 45 general position thereof with respect to the ejector lever 17 will be understood from Figure 1, it being apparent that said levers 17 form the bottoms of the record holding compartments, as 27, and in practice, I prefer to make the bottoms of the levers 17 50 rectilinear, while their top surfaces incline from about the fulcrum point 20 forwardly and rearwardly, as indicated in Figure 1, from which it will be understood that the 55 front and rear ends of the ejector lever 17 are of less thickness than the thickness of the lever at the fulcrum point 20, whereby when the record is inserted in its proper compartment 27 after it rolls back beyond 60 the fulcrum point 20, it will have a slightly accelerated movement towards its rearmost position, and in like manner, when the record is ejected by the depression of the front end of the front portion 18 of the lever 17 65 after it advances beyond the fulcrum point

20, it will have a slightly accelerated forward movement.

It will be further apparent that by the widening of the rear portion 19 of the levers, said rear portions will appear when viewed 70 from the top as seen in Figure 2, so that there will be no liability, when it is desired to eject a desired record, of said rear widened portions 19 not properly coacting with the record it is desired to eject. 75

For the purpose of showing the manner of cutting the partitions 2 from a suitable blank, I have shown in the upper portion of Figure 1 in dotted lines a partition identical with the partition 2, it being apparent that these partitions can be cut in a single operation by any suitable die or cutting implement.

In Figures 4 and 6, I have shown another form of ejector skeleton 28, wherein I employ a series of vertical, parallel, closely related partitions 29 having the contour in side elevation seen in Figure 4, each of said partitions being provided with the vertical front portion 30, the upper tongue 31 from which the rear edge 32 extends to meet the horizontal portion 33, from which extends the upwardly diverging edge 34 to form the tongue 35.

From the tongue 35 extends the rear edge 36 to meet the horizontal portion 37, from which latter extends the upwardly diverging edge 38, whereby the elongated rear tongue 39 is formed.

From the bottom of this rear tongue 39 100 extends the inclined edge 40, which forms the tongue 41, from which extends the edge 42 to meet the horizontal portion 43, from which extends the downwardly inclined edge 44 to form the tongue 45, whose front wall 105 is formed by the inclined edge 46, which extends to the vertical edge 30.

It will be apparent from Figure 4 that the edge 30 of the partition is vertical and that the edges 32 and 34 and 36 and 38 converge downwardly. The edges 40 and 42 and 44 and 46 also converge downwardly to form the tongues 41 and 45 respectively, and the cut-out portions 42, 43 and 44 form a recess as indicated at 47. The upper tongues 31 and 35 are held in assembled position by means of the spacing strips 48, which may have one or two tie rods 49 and 50. The rear elongated tongues 39 are held in position by the vertical spacing strips 51, which are held in position by one or more tie rods, as indicated at 52.

The bottom tongues 41 and 45 are held in position by the bottom horizontal spacing strips 53 and the tie rods 54 and 55, which 125 pass through the tongues 41 and 45 respectively.

It will be understood that when the partitions 29 and the respective spacing strips are assembled as seen in Figure 4, a series 130

of closely related record holding compartments 56 will be formed, as will be understood from Figure 5.

57 designates the ejector levers which are assembled to form the bottoms of the compartments, said levers having front and rear widened portions 58 and 59, which are joined by the narrower or neck portions 60, in which is the hole 61 through which the ful-

10 crum rod 62 passes.

By the provision of the rear widened portions 59, there will be no liability of the rear portion of the ejector lever missing the juxtaposed contiguous periphery of the 15 record which it is desired to eject, as is evident, and I have found from practical experiments that partitions having the upper and lower and rear tongues constructed as seen in Figure 4 are not liable to warp under any conditions of use.

It will be understood that the spacing strips 48, 51 and 53 may be of substantially the same length, so that one standard set of spacing strips may be employed throughout.

25 In the construction seen in Figure 7, I have indicated the ejector skeleton as 63, the same being formed from a plurality of partitions 64 each having its lower front 30 and rear upright parallel edges 65 and 66 and at their upper portions the upwardly converging edges 67 and 68, whereby the tongues 69 are formed, each of said tongues being spaced apart and secured in position 35 by means of the spacing strips 70 and the tie rods 71.

It will be understood that the record holding compartments are formed between a pair of partitions 64 and the bottoms of said 40 compartments may be formed of strips as indicated at 72, it being noted that said bottoms incline forwardly and are provided with the recess or seats 73 in which records drop when in their rearmost or housed position.

45 It will be seen that the bottoms 72 of the compartments incline downwardly and forwardly, so that when the record is elevated from its seat 73 by any suitable elevating or ejecting mechanism, the record will instantly roll forwardly out of the skeleton or cabinet by gravity.

It will be apparent that various types of record elevating or ejecting means may be 50 employed and in the construction seen in Figure 7, I have shown an ejector lever 74 which is composed of the front portion 75 fulcrumed at the point 76, in the rear of which, the ejector lever extends on a right 55 line as indicated at 77, thence upwardly as indicated at 78 and thence rearwardly as indicated at 79, so that it will be apparent that when the front end of the lever 74 is depressed, the rear end of the lever will 60 be elevated into the position seen in dotted

lines in Figure 7, whereupon the record will roll forwardly by gravity down the sloping surface 72 out from the front of the ejector.

In the construction shown in Figure 8, it will be understood that the partitioning devices forming the record holding compartments are composed of the bent wires 80 and 81 having the front and rear members 82 and 83 and 84 and 85 respectively. The bottom ends of the members 82 and 84 and the 75 rear ends of the members 83 and 85 may be anchored in any suitable manner and I have shown the rear ends of the members 83 and 85 as anchored in a plate or the like 86, which may be secured to or extend along 80 the back edges of the sides 87 of the skeleton or ejector.

The bottom wall or floor 88 inclines downwardly and forwardly similar to the floor 72 and is provided with the seat, slot or recess 85 89 into which a record, when in its rearmost or housed position drops, the record being ejected by means of the lever 90 whose rear portion 93 will elevate or dislodge the record from the seat 89 when the front end 92 is 90 depressed, the levers 90 being fulcrumed at the point 91, by a transverse rod passing therethrough.

In the construction seen in Figures 7 and 8, it will be apparent that the record is 95 automatically locked in its rearmost or housed position by its dropping through the slot in the forwardly inclined bottom or base.

In the construction seen in Figures 9 and 10 and 11, I use a forwardly inclined bottom 100 of the general character seen in Figures 7 and 8, but provide a different form of gravity operated levers, which retain the record in its rearmost or housed position.

In Figure 9 I have indicated partitions 94, which can be assembled and secured in their upright relationship by any of the means heretofore described, so as to form record holding compartments, the bottom or 105 base of the compartments being indicated at 95 and sloping downwardly and forwardly, the record being held in its rearmost or housed position by means of the lever 96 which is fulcrumed on the rod 97 and is provided with the front portion 98 and the rear portion 99.

110 It will be apparent from Figure 9 that the front end 98 of the lever is heavier than its rear end, and said lever normally assumes 120 the position seen in dotted lines, in which position the inner end of the portion 99 abuts against the periphery of the record so as to hold the latter in its rearmost or stowed position.

125 When it is desired for a record to be ejected, the front end portion 98 is elevated from the position seen in dotted lines to the position seen in full lines in Figure 9, whereupon the record rolls out of its compartment.

ment by gravity, it being understood that the lever 96 automatically assumes, at all times the position seen in dotted lines in Figure 9.

5 In Figure 10 I have indicated the record holding compartment as being formed from the partitions 100, having the bottom floor 101, which inclines downwardly and forwardly and has slots 102 at its front end, in 10 which levers 103 are located, said levers being fulcrumed at the point 104 and the front portion 105 of said lever being heavier than the rear portion, so that the lever at all times normally assumes the position seen 15 in Figure 10, in which its rear or inner end 106 contacts with the periphery of the record to hold it in its rearmost or stowed position.

20 In Figure 11 I have shown the record holding compartments formed by the partitions 107, which have the vertical front edges 108, the front upper tongue 109, rearwardly inclined edge 110, and the rear horizontal portion 111, which terminates in the rear vertical edge 112.

25 The top tongues 109 may be assembled by means of the spacing strips 113 and tie rods 114 of the same construction as already described.

30 The bottom floor 115 inclines forwardly and downwardly and has pivoted therein a lever 116 whose rear edge contacts with the lower forward periphery of the record to hold the same in its rearmost or stowed position, while the front end of said lever contacts with the top of the rear 117 of the lever 118 whose front end 119 is adapted to be actuated by a finger of the operator applied to the front of the lever 118.

35 The compound levers 118 and 116 normally appear as seen in full lines in Figure 4, the rear of the lever 118 being heavier than its front end and the front of the lever 116 being heavier than its rear portion, but when it is desired to eject the desired record, 40 it is only necessary to depress the forward end of the lever 119 so that the two levers assume the position seen in dotted lines in Figure 11, whereupon the record will roll forwardly by gravity into the hands of the 45 user.

50 In Figures 16 and 17, I have shown another form of ejector 120, which is composed of partitions 121, which are provided with the vertical front rear edges 122 and 123 and the upwardly converging edges 124 and 125, which are held between the spacing strips 126 by means of the tie rods 127, which properly and accurately space apart the upper ends of the partitions, the lower ends 55 thereof being spaced apart by means of the tongues 128, which extend upwardly from the forwardly and downwardly inclined base 129, which has the rear vertical wall 130 and the front vertical wall 131, said 60 tongues 128 being omitted from Figure 16.

The levers 132 are under the bottom 129 and are fulcrumed at the point 133 and provided at the rear with a trough shaped portion 144 and at the front with a rectilinear portion 145, which projects through the 70 slots 146 in the front wall 131.

In constructing the forwardly and downwardly inclined metallic bottom or base member 129, I preferably make the same from a blank of thin sheet metal as seen in 75 Figure 12 which I have indicated in its flat state as 147.

By suitable die or cutting, pressing or stamping mechanism, I simultaneously form the angular slits 148, seen in Figures 12 and 80 13 and I also simultaneously form the slots 146, and by a subsequent stamping, or pressing operation I may produce the finished base member seen in Figure 17, the tongue members 128 being bent up so as to appear 85 as seen in Figure 17 and the top edge 149 and the bottom edge 150 being bent downwardly to form the members 130 and 131 respectively, seen in Figure 17.

By this construction a very cheap and 90 efficient metallic base member is formed by a minimum number of operations out of thin sheet metal.

When the tongues 128 are bent in the position seen in Figure 17, it will be apparent 95 that a slot of substantially the length of the aligning trough shaped portion 144 of the lever 142 will be formed, into which the bottom periphery of a record will drop when in its rearmost or stowed position.

100 When the levers 132 are assembled, it will be apparent that their front ends project through and are guided by the slots 136, so that the levers will be positioned and guided during their oscillations to eject the records, 105 the latter being ejected by the depression of the front ends of the levers.

In Figures 18 to 21, I have shown another form of skeleton 151, wherein the front is composed of a vertical plate 152, 110 having the staggered tongues 153 punched from the rear thereof, by substantially the same method as described with reference to Figures 12 to 14, as will be understood from Figure 21, which is a perspective view 115 of the rear of the front plate after the formation of the tongue 153 in vertical rows. The partitions 2 which are the same as seen in Figure 1, can have their front edges 3 inserted between the vertical rows of rear 120 metallic tongues 153, whereby the fronts of the partitions are properly secured, after which the tongues 4, 7, 12 and 13 are secured by spacing strips and tie rods, as seen in Figure 1, so that the front of the 125 skeleton appears as seen in Figure 18 and its side as seen in Figure 19, the bending, stamping or pressing of the staggered tongues 153 rearwardly as seen in Figure 21 forming upright continuous vertical 130

slots 154 in the rear of the front metal plate 152, through which the records are inserted.

The bottoms of the record holding compartments are formed by levers 17.

5 I have shown the front appearance of these backwardly bent tongues 153 at the left of Figure 18, but have omitted them from the right thereof for the sake of clearness of illustration. Figure 22 shows the 10 partitions 29 having their fronts secured to the metal front 152.

It will now be apparent that I have devised a novel and useful phonographic disk record cabinet, which embodies the features 15 of advantage enumerated as desirable in the statement of the invention and the above description, and while I have in the present instance shown and described preferred embodiments thereof which will give in 20 practice satisfactory and reliable results, it is to be understood that the same is susceptible of modification in various particulars without departing from the spirit or scope of the invention or sacrificing any of its 25 advantages.

Having thus described my invention, what I claim as new and desire to secure by Letters Patent is:—

1. In a record container or ejector, a plurality of vertical, closely related, parallel compartments formed by partitions having upper, lower and rear tongues, the bottom portions of said partitions being cut away, and ejector levers forming the bottoms of 35 said compartments.

2. In a record container or ejector, a plurality of vertical, closely related, parallel compartments formed by partitions having upper, lower and rear tongues, the bottom 40 portions of said partitions being cut away, and ejector levers forming the bottoms of said compartments, said ejector levers having their top surfaces from their fulcrum point inclined forwardly and rearwardly.

45 3. In a record container or ejector, a plurality of vertical, closely related, parallel compartments formed by partitions having upper, lower and rear tongues, the bottom portions of said partitions being cut away, and ejector levers forming the bottoms of 50 said compartments, said ejector levers having their top surfaces from their fulcrum

point inclined forwardly and rearwardly, and said levers having their rear portion wider than their forward portion.

55

4. In a record container or ejector, a plurality of partitions having a plurality of upper, lower and rear tongues, spacing strips, and tie rods common to said tongues for holding said partitions in assembled 60 position to form compartments, and ejector levers pivoted in the lower portion of said compartments to form the bottoms thereof.

5. In a record container or ejector, a plurality of partitions having a plurality of upper, lower and rear tongues, spacing strips, and tie rods common to said tongues for holding said partitions in assembled 65 position to form compartments, and ejector levers pivoted in the lower portion of said 70 compartments to form the bottoms thereof, the front and rear portions of said levers being wider than said intermediate portions.

6. An ejector skeleton having its front formed by a metallic plate having rearwardly deflected staggered tongues forming vertical slots, said tongues being arranged in vertical rows, vertically arranged partitions having their front vertical edges positioned between said tongues, and means for spacing apart and securing the top, rear and bottom portions of said partitions, in combination with ejector levers having their fulcrum rod passing through the lower 75 front portions of said partitions.

80 7. An ejector skeleton having its front formed by a metallic plate having rearwardly deflected staggered tongues forming vertical slots, said tongues being arranged in vertical rows, vertically arranged partitions having their front vertical edges positioned between said tongues, and means for spacing apart and securing the top, rear and bottom portions of said partitions, in combination with ejector levers having their fulcrum rod passing through the lower 85 front portions of said partitions, the rear portions of said levers being wider than their front portions.

ERLE H. HAND.
